CLAMP

Charles J. Kotchi, Chicago, Ill., assignor, by direct and mesne assignments, to Joseph Pendelick, Chicago, Ill.

Application March 27, 1940, Serial No. 326,241

1 Claim. (Cl. 144—304)

This invention relates to improvements in clamps particularly adapted though not necessarily limited in use as a work holding clamp, and one of the objects of the invention is to provide an improved device of this character which will serve as a clamp as well as a vise, and which embodies a clamping screw or element adjustable to effect a clamping action on the work, and improved means for increasing or compounding such clamping action after the screw has reached the limit of its movement in the clamping direction.

A further object is to provide an improved clamp of this character, the main or body portions of which may be constructed from sheet material bent or stamped into shape, thereby not only decreasing the cost of manufacture but providing a clamp which will be comparatively light in weight and which will be effective and efficient in operation.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which

Figure 1 is a perspective view of a clamp of this character constructed in accordance with the principles of this invention.

Figure 2 is a longitudinal vertical sectional view.

Figure 3 is a detail sectional view taken on line 3—3 Figure 2.

Figure 4 is a detail sectional view taken on line 4—4 Figure 2.

The clamp consists essentially of two jaw members 10—11 which are of substantially L shape configuration and these members are constructed of sheet material stamped or formed into shape so as to provide jaw members which are of a hollow or channel formation.

The numeral 12 designates generally a connecting member which is also formed of sheet material and is of channel formation, the extremities of the member 12 being preferably rounded as at 13.

This channel member 12 is disposed between the jaw members 10—11 and is seated within the members, the respective jaw members being pivotally connected as at 14—15 with the connecting member 12, spacing blocks 16 being disposed within the connecting member 12 at the

pivot points to serve as reinforcing means as well as bearings for the pivots.

The ends of the members 10—11 overlap as at 17—18, the parts being preferably cut away for that purpose.

The connecting member 12 spans the joint between the members 10—11 and the overlapping portions are of such an extent and so shaped so as to permit a free and limited pivotal movement of the jaw members 10—11 about their pivots 14—15.

Within the body portion of the member 10 is a nut 19 held in position in any suitable manner and threaded through the nut is a screw 20 which also passes through the member 10, the screw being provided with an operating handle 21.

The end of the screw 20 contacts the connecting member 12 and if desired the member 12 may be reinforced as at 22 at the point where the end of the screw contacts the same.

At the upper end of the jaw 10 and housed therein is arranged a block 23 which serves as a clamping member or anvil and at the upper end of the member 11 is a block 24 housed therein and this block together with the block 23 are secured in position in any suitable manner.

Threaded through the block 24 and the jaw member 11 is a screw 25 on the forward end of which is pivotally mounted a clamping member 26 that co-operates with the block 23 to clamp the work 27 therebetween. This screw 25 is of a length greater than the distance between the jaws 10—11 so as to permit of the clamping of relatively small articles, and at the other end of the screw is arranged an operating handle 28.

With this construction it will be manifest that the jaws and the connecting member 12 being formed of sheet material bent or stamped into shape, a very rigid construction will be provided while at the same time it will be comparatively light in weight.

In use and when the parts are in the position shown in Figure 2, the screw 25 is adjusted so that the head 26 and the block 23 will clamp the work 27.

If it is desired to secure a greater pressure upon the work 27, the screw 20 is adjusted and this adjustment through the medium of the pressure of the screw 20 upon the connecting member 12 will cause the jaw 10 to have a tendency to move toward the jaw 11 about its pivot 14. If the movement of the jaw 10 about its pivot 14 is of any considerable extent, the portion 17 of the jaw 10 which overhangs the portion 18 of

the jaw 11 will contact the portion 18 and tend to move the jaw 11 about its pivot 15 toward the jaw 10.

With this improved construction it will be manifest that there is not only provided an efficient clamp, but a device which will also serve in the nature of a vise which will be comparatively light in weight but rigid and strong in construction.

While the preferred form of the invention has been herein shown and described, it is to be understood that various changes may be made in the details of construction and in the combination and arrangement of the several parts, within the scope of the claim, without departing from the spirit of this invention.

What is claimed as new is:

A clamp embodying two rigid substantially L shaped members, one of the arms of one member being arranged in longitudinal alinement with an arm of the other member, the other arms of said members being spaced and substantially parallel, a link disposed entirely within the space

between the said alined arms and the extremities of the other arms and pivotally connected by its ends respectively to the said members at points remote from the proximate ends of said alined arms, the free end of the other arm of one of said members constituting a work engaging area, a screw passing through the free end of the opposite arm of the other member and cooperating with said work engaging area to clamp the work therebetween, and a screw passing through one of the said alined arms and engaging the said link intermediate its ends and remote from said pivotal connections to effect a relative pivotal movement of the said members after the clamping action is effected, to impart a further clamping action to one of said members upon the work, the proximate extremities of said alined arms overlapping and serving only to effect a pivotal movement of one of the members when the other member is pivotally moved to any considerable extent.

CHARLES J. KOTCHI.
